ABSTRACT: In apparatus for intercepting the air film rotating with a grinding wheel for positive supply of coolant to the grinding point of the grinding wheel, an arcuate baffle plate adjacent to a coolant nozzle for supplying coolant and extending in parallel with the axis of the grinding wheel is pivotally mounted on the outer end of a cover plate covering a portion of the periphery of the grinding wheel to take up the air film and deflect the same away from the periphery of the grinding wheel.

APPARATUS FOR INTERCEPTING AIR FILMS ROTATING WITH GRINDING WHEELS

BACKGROUND OF THE INVENTION

This invention relates to an improved apparatus for intercepting an air film rotating with a grinding wheel.

When a grinding wheel operates a workpiece it is necessary to ensure positive supply to coolant to the working point of the grinding wheel.

Prior apparatus for intercepting an air film rotating with the grinding wheel 1' comprises an intercepting baffle plate 17' adjustably secured to a coolant nozzle 10' by means of a bolt 19', as shown in FIG. 1. With this construction, however, as the spacing between a front cover 13' secured to a guard 4' for the grinding wheel 1' and the coolant nozzle 10' is relatively narrow, when the gap between the intercepting baffle plate 17' and the generating line of the grinding wheel is adjusted as the wheel wears, the intercepting baffle plate tends to incline, thus rendering it difficult to adjust the gap. Further as the intercepting baffle plate is mounted on the coolant nozzle, variation in the position of the coolant nozzle results in the variation of the gap thus rendering it difficult to completely intercept the air film rotating with the grinding wheel.

SUMMARY OF THE INVENTION

It is therefore an object of this invention to provide an improved apparatus for intercepting an air film rotating with a grinding wheel which can ensure a positive supply of coolant to the working point of the grinding wheel without being interfered by the rotating air film and which can be adjusted readily as the diameter of the grinding wheel varies.

According to one embodiment of this invention there is provided an apparatus for intercepting the air film rotating with a grinding wheel composing a grinding wheel, a stationary guard, a front cover pivotally mounted on the guard to cover a portion of the periphery of the grinding wheel, an arcuate baffle plate extending in parallel with the axis of the grinding wheel, to take up the air film and deflect it away from the peripheral surface of the grinding wheel and means to pivotally mount the baffle plate on the outer end of the front cover whereby to discharge the air film intercepted by the baffle plate through an opening defined by the baffle plate and the front cover. A coolant supply nozzle is positioned behind the baffle plate so that it is possible to positively the coolant to the working point of the grinding wheel without being interfered by the rotating air film.

BRIEF DESCRIPTION OF THE DRAWINGS

Further objects and advantages of the present invention will become apparent and the invention will be better understood from the following description, reference being made to the accompanying drawings in which:

FIG. 1 shows a side elevation, partly in section, of a prior art apparatus for intercepting an air film rotating with a grinding wheel;

FIG. 2 is a view similar to FIG. 1 illustrating one embodiment of this invention and

FIG. 3 is a partial perspective view showing the manner of a mounting the air film intercepting apparatus shown in FIG. 2.

DESCRIPTION OF THE PREFERRED EMBODIMENT

Referring now to FIGS. 2 and 3 of the accompanying drawings there is shown a grinding wheel 1 clamped between flanges 3 secured to a wheel spindle 2 which in turn is rotatably supported by a wheel support, not shown. A guard 4 is secured to the wheel support and a support 5 is secured to the upper surface of the guard 4 by means of a bolt 6. A coolant pipe 7 is secured to the support 5 by means of clamping plates 8 and a bolt 9. A coolant nozzle 10 is threadably connected to the pipe 7 by screw threads 7a formed on the outer end of coolant pipe 7, and a suitable coolant is supplied to the pipe 7 from a suitable coolant supply source, not shown, dur-

ing grinding operation and is discharged from a discharge opening 10a of the coolant nozzle 10 onto the working point of the grinding wheel or a point at which a workpiece 11 to be ground is urged against the periphery to the grinding wheel. 5 As shown a cock 12 is included in the coolant pipe 7 to control the flow quantity of the coolant discharged through the discharge opening 10a of the coolant nozzle. The position of the coolant nozzle can be adjusted in the horizontal and vertical direction and in the direction perpendicular to the plane of the sheet of the drawing so that the discharge nozzle 10a opposes the point of contact between the grinding wheel and the workpiece 11 or the working point of the grinding wheel. A front cover 13 is mounted on the guard 4 by means of a pivot pin 12a extending through openings of a hinge 4a formed on the guide so that the front cover 13 may swing in parallel with the axis of the grinding wheel. An arcuate slot 13a having a center at the axis of the pivot pin 12a is provided for each side plate of the front cover to receive a bolt 15 which is 10 threadably connected to a side cover 14 of the guard 4 through a washer 16 so as to connect the cover 13 to the side cover 14 with a suitable spacing between the cover 13 and the periphery of the grinding wheel 1.

The intercepting apparatus 17 comprises an arcuate baffle plate 17b extending in parallel with the axis of the grinding wheel and a pair of circular side plates 17a welded to the opposite ends of the baffle plate 17b thus forming a troughlike configuration. The side plates 17a are secured to the opposite sides of the outer end of the cover 13 by means of bolts 19 and washers 18. The inner edge of the baffle plate 17b confronting to the periphery of the grinding wheel is formed with a notch 17c having a width slightly wider than that of the grinding wheel and the remaining portions 17d of the baffle plate 17b are extending along the side surfaces of the grinding wheel. 15 When bolts 19 are loosened the air film intercepting apparatus 17 may be rotated about these bolts 19 to vary the angle of intercepting the air film rotating with the grinding wheel at or near the peripheral surface thereof. Thus, during the grinding operation of the grinding wheel the air film rotating therewith is taken up with the arcuate baffle plate 17b deflected away from the surface of the grinding wheel by being guided by the arcuate inner surface thereof and is finally discharged in the opposite direction to the air film which is caused along the 20 outer surface of the grinding wheel 1 as viewed in FIG. 2 through an opening defined among the lower edge of the cover 13, the upper or outer edge of baffle plate 17b and side plates 17.

As above described since according to this invention the 25 rotating air film intercepting apparatus 17 is bolted to the opposite sides of front cover 13, fine adjustment of the gap between the baffle plate 17b and the generating line of the grinding wheel can be readily provided by merely loosening bolts 19 and then rotating intercepting apparatus about these 30 bolts. Moreover as respective side plates 17a of the air film intercepting apparatus 17 are guided by the side surface of cover 13 and since the side plates 17a are rotatably mounted by the bolts 19 the arcuate baffle plate 17b does not incline with respect to the generating line of the grinding wheel thus 35 maintaining uniformity of the width of the gap between the inner edge of the arcuate baffle plate 17a and the generating line of the grinding wheel. As the air film rotating with the peripheral surface of the grinding wheel is taken up by the inner edge of the arcuate baffle plate and is then discharged 40 upwardly along the arcuate inner surface of the baffle plate, the air film is nearly perfectly intercepted near the working point of the grinding wheel. Consequently, the coolant discharged from the discharge opening 10a of the coolant nozzle 10 is positively supplied to the working point without being 45 intercepted by the rotating air film.

In the above-described embodiment, the front cover 13 and the coolant nozzle 10 are manually adjusted independently of each other in accordance with decrease in the diameter of the 50 wheel 1 due to wear thereof.

It is, however, possible to automatically adjust the front cover and the coolant nozzle in unison in accordance with decrease in the diameter of the wheel due to wear thereof by slidably mounting the front cover and the coolant nozzle in a body on the stationary wheel guard and by effecting slide movement thereof in accordance with decrease in the diameter of the wheel.

What is claimed is:

1. In apparatus for intercepting the air film rotating with a grinding wheel comprising a rotary grinding wheel, a stationary front cover to cover a portion of the periphery of said grinding wheel, a coolant nozzle for supplying coolant to the grinding point of said grinding wheel, and a baffle plate disposed between said cover plate and said coolant nozzle to take up 15 said air film and to deflect the same away from the peripheral

surface of said grinding wheel, the improvement which comprises an arcuate baffle plate extending in parallel with the axis of said grinding wheel, and means to pivotally mount said baffle plate on said cover plate whereby to discharge the air film intercepted by said baffle plate through an opening defined by said baffle plate and said front cover.

5 2. An apparatus as defined in claim 1 wherein said arcuate baffle plate is provided with side plates on the opposite ends thereof and secured to the opposite sides of said cover plates 10 at its outer ends.

15 3. An apparatus as defined in claim 1 wherein the inner edge of said arcuate baffle plate closely confronting to the periphery of said grinding wheel is notched to receive the same.
